LOCK-STITCH SEWING MACHINE

John D. Karle, Roselle Park, N. J., assignor to The
Singer Manufacturing Company, Elizabeth,
N. J., a corporation of New Jersey

Application April 8, 1939, Serial No. 266,786

14 Claims. (Cl. 112—181)

This invention relates to lock-stitch sewing machines more particularly of the type having a reciprocating eye-pointed needle and a complementary loop-taker with which is associated a bobbin of under thread about which loops of the needle-thread are cast by the loop-taker in the formation of stitches.

The problem of supporting the bobbin for the free casting of the needle-loops thereabout, in a machine of the type referred to, has received much attention in the development of the lock-stitch sewing machine art and, at the present time, the conventional practice is to dispose the bobbin in a non-rotary bobbin-case having a peripheral bearing-rib received in an internal groove in the rim of a cup-shaped rotary loop-taking hook. During long runs at high speeds, the friction between the stationary and moving bearing surfaces of the bobbin-case and hook overheats the parts, making them too hot to handle in bobbin replenishment and causing premature and destructive wear. Various attempts have been made to reduce or eliminate this objectionable friction but no solution has been proposed which has the requisite simplicity, effectiveness and freedom from drawbacks to gain recognition over the clean running conventional hook and bobbin-case disclosed in the U. S. Patent to C. A. Kessler, No. 1,995,278 of Mar. 19, 1935.

The present invention has for an object to provide simple and practical means to materially reduce raceway friction and wear in a sewing machine rotary hook more particularly of the type shown in said Kessler patent, without sacrifice of the clean running, high-speed sewing characteristics of such hook.

Further objects of the invention will in part be obvious and in part hereinafter appear.

The invention will be understood from the following detailed description taken in connection with the accompanying drawings of which Fig. 1 is a side elevation, partly in section, of a sewing machine embodying the invention in a preferred form. Figs. 2 and 3 are sectional views, on a larger scale, of the hook and bobbin-case-supporting mechanism of Fig. 1, at two different instants of a stitch-forming cycle. Fig. 4 is a bottom plan view of the bobbin-case-supporting rod-reciprocating mechanism. Fig. 5 is a perspective view of the rotary hook element of the present improvement. Fig. 6 is a perspective view of the bobbin-case element. Fig. 7 is a longitudinal vertical sectional view of a modified form of the invention. Fig. 8 is a similar view with the bobbin-

case supporting means of Fig. 7 withdrawn for passage of the needle-thread-loop. Fig. 9 is a left end elevation of the device shown in Fig. 7, and Fig. 10 is a perspective view of a cam element included in the form of the invention shown in Figs. 7, 8 and 9.

Referring first to the preferred embodiment of the invention illustrated in Figs. 1 to 6, both inclusive, 1 represents the bed of a sewing machine from which rises the conventional standard 2 of the overhanging bracket-arm 3 terminating in the head 4. The main shaft 5 carrying the balance wheel 6 and power-receiving belt-pulley 7 is journaled within the overhanging arm 3 and has the conventional crank 8 and link 9 connections for reciprocating the needle-bar 10 carrying the eye-pointed needle 11. The shaft 5 also drives the conventional link take-up 12 which handles the needle-thread in the usual manner. Geared to and driven by the top shaft 5, in one-to-one relation, is the vertical shaft 13 to the lower end of which is secured the crank-head 14 and bevel gear 15; the crank-head carrying the crank-pin 16 and slide-block 34.

Journalized in bearing bushings 17, 18, below the bed 1, is the tubular hook-shaft 19 to the left end of which is secured the cup-shaped rotary hook-body 20 having the usual internal peripheral bearing groove 21 for the peripheral bearing rib 22 of the bobbin-case 23 which is conventional in all respects with the exception of the hole 24 formed in its rear face coaxial with the central arbor pin 25. A slightly increased working clearance over conventional practice is preferably allowed between the juxtaposed bearing surfaces of the rib 22 and groove 21. Except for the hole 24, which is coaxial with the peripheral bearing rib 22, and the slightly increased raceway bearing clearance, the hook 20 and bobbin-case 23 are preferably constructed substantially in accordance with the disclosure of the said Kessler patent; the thread-case 23 being restrained against rotation by the usual rotation-restraining bar 26 having a tongue 27 which loosely enters a notch 28 in the front face of the bobbin-case. The bobbin-case 23 also has the usual gap in its bearing rib 22 affording the stationary loop-catching shoulder 29 which detains one limb of the needle-thread loop after it is seized from the needle by the beak 20' of the rotary hook, in the operation of casting the loop about the bobbin-case.

The non-rotary bobbin-case 23 is, in accordance with the present invention, supported truly centrally within the field of action of the hook 20

by an endwise reciprocatory rod 30 which extends within and lengthwise of the tubular hook-shaft 19 fitted at its opposite ends with bearing bushings 31 through which the rod 30 extends. At its right-hand end, the rod 30 has fixed to it a rectangular yoke 32 having a slot 33 for the crank slide-block 34. A nut 35 and washer 36 cooperate with the flat bottomed face of the crank-head 14 to confine the yoke 32 and rod 30 against rotation with the shaft 19.

The hook-shaft 19 has fixed to its rearward end, a bevel gear 37 of half the pitch-diameter of the bevel gear 15 with which it meshes and is driven at twice the speed of the top-shaft 5.

When the rod 30 is in the hole 24, it sustains the weight of the bobbin-case and relieves the peripheral bearing surfaces of friction from this cause. The working position of the free end of the rod 30 and the radius of the crank 16 are so contrived that the free end of the rod 30 is in the hole 24 as long as possible and is withdrawn from the hole but a small fraction of the time of one stitch-forming cycle, as shown in Fig. 3, for the passage of the inner limb 38 of the cast needle-thread-loop. For example, the radius of the crank 16 may be $\frac{1}{2}$ inch giving a stroke of $\frac{1}{8}$ inch to the rod which may penetrate the bobbin-case to a depth of $\frac{1}{4}$ inch and can be timed to be in the bobbin-case during the entire idle rotation of the hook and the first and last portions of the loop-casting rotation. In fact, the rod 30 of the model machine illustrated is out of the hole 24 for a time period equal to 90° of rotation of the hook-shaft 19, which is $\frac{1}{8}$ of a stitch-forming cycle.

The free end of the rod 30 or the mouth of the hole 24, or both, should preferably have their corners broken or slightly beveled, to insure pick up of the bobbin-case by the rod 30 when the machine is being turned over slowly or at moderate speeds. At high speeds it is believed the bobbin-case practically floats in space during the exceedingly short time intervals that the rod 30 is out of the hole 24.

In the embodiment of the invention shown in Figs. 7, 8, 9 and 10, two opposed central reciprocatory rods or pins 39 and 40 are used to support the thread-case 41 which is like the thread-case 23 in all respects except that it has, in addition to a hole 42 in its inner face, a coaxial hole 43 in the tip end of the center post or arbor 25. The hole 42 is not as deep as the hole 24 in the bobbin-case 23 and the stroke of the rod 40 may be considerably reduced by using a crank-pin like the crank-pin 16 but of reduced eccentricity.

The pin 39 is mounted in an arm 44 which is swiveled on the pin 45 but is normally locked by the spring-pressed plunger 46 to the segmental plate-like head 47 of a sleeve 48 slidably supported by the projecting end of a bearing bushing 49 fixed in the bed-lug 12. The sleeve 48 has an upstanding arm 50 at its inner end to which is fixed a headed pin 51 slidable in a guide-bore 52 of the bed-lug 12 and biased in one direction by the spring 53.

Mounted in the sleeve 48 on the transverse pin 54 are the rollers 55 which are held separated by the spacer 56 and are acted upon by the diametrically opposed cam rises 57 on the face 58 of the head 59 of the shaft 60 journaled in the bearing bushing 49 and carrying a gear 61 which is driven by the pinion 62 on the hook-shaft 19, Fig. 7. The gear ratio of the gears 62, 61 is one to four so that the cam-shaft 60 makes one-half

revolution for two revolutions of the hook-shaft. The cams 57 are timed to withdraw the pin 39 from the hole 43 simultaneously with the withdrawal of the pin 40 from the hole 42 for passage of the cast needle-thread-loop, as shown in Fig. 8.

The latch-pin 46 may be withdrawn from the upper hole in the segmental plate 47 and the arm 44 swung counter-clockwise, Fig. 9, to a horizontal position, to expose the face of the bobbin-case 41 for bobbin removal and replenishment.

Having thus set forth the nature of the invention what I claim herein is:

1. In a sewing machine, a loop-casting hook, a tubular rotary shaft carrying said hook, a non-rotary centrally apertured bobbin-case supported by said hook within its loop-casting field of action, a rod disposed coaxially of and within said tubular shaft, and means to reciprocate said rod endwise to cause it to intermittently enter said bobbin-case between loop-casting operations.

2. In a sewing machine, the combination with a rotary loop-taking hook and an apertured stationary bobbin-case having interengaging circular means to retain the bobbin-case within the field of action of said hook, of bobbin-case-supporting means including reciprocatory spindle means arranged to enter the aperture in said bobbin-case for the support of the latter for more than one complete rotation of said hook and to withdraw from said bobbin-case momentarily for passage of the needle-thread-loop.

3. In a sewing machine, a loop-taker, a hollow loop-taker driving shaft, an endwise reciprocatory rod in said shaft, and a non-rotating bobbin-case journaled in said loop-taker and intermittently engaged by said rod for support of said bobbin-case.

4. In a sewing machine, a loop-taker, a hollow loop-taker driving shaft, an endwise reciprocatory rod in said shaft, and a non-rotating bobbin-case journaled in said loop-taker and formed with a central aperture intermittently entered by said rod for support of said bobbin-case.

5. In a sewing machine, a bobbin-case having a peripheral bearing and an axial arbor provided with an axial hole, a rotary hook, in which the peripheral bearing of said bobbin-case is loosely journaled, a tubular hook-driving shaft, and an endwise reciprocatory rod disposed in said shaft and intermittently entering said axial hole to support said bobbin-case and take the weight of the latter off of said peripheral bearing.

6. The combination with a rotary loop-casting hook and a stationary apertured bobbin-case loosely journaled in said hook, of a tubular hook-supporting drive-shaft terminating at one end adjacent said bobbin-case, a reciprocatory rod extending lengthwise of and within said tubular drive-shaft, and means to reciprocate said rod endwise so as to intermittently project one end thereof beyond the end of said hook-shaft and into the aperture in said bobbin-case to support the latter, said rod-reciprocating means acting to withdraw said rod from said bobbin-case momentarily for passage of the cast needle-loop therebetween.

7. A sewing machine having a frame including a bed and overhanging bracket-arm, a reciprocatory needle carried by said bracket-arm, a tubular rotary hook shaft journaled in said bed, a rod disposed in and projecting from said hook-shaft, a rotary hook complementary to said needle in the formation of stitches, a bobbin-case journaled in

said rotary hook and having an axial aperture entered by the projecting end of said rod, and means to reciprocate said rod endwise into and out of said axial aperture at the frequency of needle-reciprocation.

8. In a sewing machine, the combination with the usual frame and top needle-driving shaft, of a vertical shaft driven one-to-one by the needle-driving shaft and having at its lower end a gear and a crank, a lower tubular shaft geared to be driven by said gear at two or more times the speed of the needle-driving shaft, a rotary hook carried by said lower tubular shaft, a non-rotary bobbin-case loosely journaled in said rotary hook and formed with an aperture coaxial with said tubular shaft, and a reciprocatory rod slidable endwise of and within said tubular shaft and actuated by said crank to intermittently enter said aperture and support said bobbin-case clear of said rotary hook.

9. In a sewing machine, a loop-casting hook, a bobbin-case, a pair of oppositely disposed pins to support the bobbin-case within the field of action of the hook, means to withdraw said pins from said bobbin-case substantially simultaneously and in time to permit passage of a thread-loop being cast by the hook about the bobbin-case, and means to hold said bobbin-case in position for re-engagement by said pins.

10. In a sewing machine, a pair of opposed coaxially arranged pins, a bobbin-case supported by said pins, a rotary loop-casting hood having a field embracing said bobbin-case, means to simultaneously and momentarily withdraw said pins from said bobbin-case for the passage of a cast needle-loop, and manually operable means to swing one of said pins to one side for access to said bobbin-case for replenishment of the bobbin-thread supply.

11. In a sewing machine, the combination with a rotary loop-casting hook and a non-rotary apertured bobbin-case confined within the field

of action of said hook, of a crank-driven endwise reciprocatory rod arranged to intermittently enter the aperture in said bobbin-case for the support of the latter for discontinuous time periods 5 each greater than one-half of the duration of a stitch-forming cycle.

12. The combination with a reciprocatory eye-pointed needle and a rotary hook making a plurality of complete rotations for each complete reciprocation of said needle, of a bobbin-case confined within the field of action of said hook and formed with a central aperture, and an endwise reciprocatory rod arranged to intermittently penetrate the aperture in said bobbin-case 15 far enough for the support of the latter during the entire idle rotation of said hook and for the beginning and final portions of the loop-casting rotation of the latter.

13. The combination with a reciprocatory eye-pointed needle and a rotary hook making a plurality of complete rotations for each complete reciprocation of said needle, of a bobbin-case confined within the field of action of said hook and formed with a central aperture, and a crank-driven endwise reciprocatory rod arranged to intermittently penetrate the aperture in said bobbin-case 20 far enough for the support of the latter during the entire idle rotation of said hook and for the beginning and final portions of the loop-casting rotation of the latter.

14. In a sewing machine, a rotary loop-casting hook formed with a raceway, hook driving means, a non-rotary axially apertured bobbin-case confined by said raceway within the loop-casting 25 field of action of said hook, and an endwise reciprocatory rod arranged on the same side of the hook as the hook-driving means to enter the axial aperture in said bobbin-case and relieve the bobbin-case and hook of their tendency to overheat because of friction at said raceway.

JOHN D. KARLE.
